UNITED STATES PATENT OFFICE.

HENRY PYE, OF PHILADELPHIA, PENNSYLVANIA, ASSIGNOR TO FLEMING BROTHERS, OF SAME PLACE.

DESIGN FOR STOCKING-FABRIC.

Specification forming part of Design No. 5,228, dated August 22, 1871.

To all whom it may concern:

Be it known that I, HENRY PYE, of the city of Philadelphia and State of Pennsylvania, have invented and produced a new and original Design for Stocking, of which the following is a specification:

The nature of my design is fully represented in the accompanying photographic illustrations, to which reference is made.

Two series of bands, A B, of equal width, alternate with each other from the top to the toe of the stocking. The bands A are of scarlet color, having a green streak, *a*, in the middle. The

bands B have an orange streak, *b*, in the middle. On each side the streak is black, blended to a gray, and terminating in a white streak, *d*, and then a purple border, *e*, with a row of stitches in groups of white and green colors. Any other contrasting colors might be used instead of those above referred to.

I claim as my invention—

The design for stocking, as shown and described.

HENRY PYE.
